UNITED STATES PATENT OFFICE.

JOSHUA UPHAM, OF SALEM, MASSACHUSETTS.

IMPROVEMENT IN COMPOUNDS FOR EXTINGUISHING FIRES.

Specification forming part of Letters Patent No. 8,495, dated November 4, 1851.

To all whom it may concern:

Be it known that I, JOSHUA UPHAM, of Salem, in the county of Essex and State of Massachusetts, have invented a new and useful Mode of Preventing the Combustion or Destruction of a Building by Fire; and I do hereby declare that the same is fully described in the following specification.

My process consists in introducing into an apartment or building when it is on fire a mixture of twenty parts of sulphur and three parts of niter, combined together and either previously set on fire or placed where the flames in such apartment can gain access to it. The mode of proceeding which I advise is to put the compound in a common iron vessel, shallow pot, or skillet of sufficient capacity to contain the quantity required of it, and introduce each vessel so charged, and with its contents set on fire, into the apartment while it is on fire, taking care to close the windows and doors thereof, if possible. In case of a navigable vessel, if the fire takes in the cargo or hold, the compound of sulphur and niter may be introduced in any proper manner, and, if set on fire or placed in contact with the fire, sulphurous-acid gas will be evolved in great quantities, and by its affinity for the oxygen in the hold will soon absorb such quantities thereof as to cause the fire to

go out. So, in case of a building on fire, the sulphurous-acid gas produced during the combustion of the compound of sulphur and niter will soon fill the room, provided there be a sufficient quantity of such compound—say about a dozen pounds thereof to an apartment about twenty feet square—it will shortly extinguish the fire. The object of using so large a quantity of niter is to facilitate combustion of the sulphur and generate the gas as soon as possible.

I am aware that it is known that sulphurous-acid gas will extinguish the flame of a taper or any such like small flame. I therefore do not claim such as my invention or discovery; but

What I do claim is—

The application of a compound of sulphur and niter, in a state of combustion, within a room or apartment on fire, for the purpose of extinguishing the fire tending to destroy said room or building thereof.

In testimony whereof I have hereto set my signature this 27th day of March, A. D. 1851.

JOSHUA UPHAM.
